RENEWABLE BLADE KNIFE

Lester J. Jorge, Chappaqua, N. Y.

Application October 7, 1955, Serial No. 38,287

Term of patent 14 years

(Cl. D22—3)

FIG. 1

FIG. 2

FIG. 3

FIG. 4

FIG. 5

Fig. 1 is a top plan view of a renewable blade knife comprising the design of the present invention;

Fig. 2 is a side view as seen from the right side of Fig. 1;

Fig. 3 is a bottom plan view as seen from the right side of Fig. 2;

Fig. 4 is an enlarged end elevational view as seen from the top or point end of Fig. 1; and

Fig. 5 is an end elevational view of the same scale as Fig. 4, as seen from the bottom or handle end of Fig. 1.

I claim:

The ornamental design for a renewable blade knife, substantially as shown.
